UNITED STATES PATENT OFFICE.

ARIE DE VOS, OF MINNEAPOLIS, MINNESOTA, ASSIGNOR OF ONE-HALF TO S. S. STILL, OF DES MOINES, IOWA.

ELECTRICALLY-WOUND CLOCK.

No. 872,909.

Specification of Letters Patent.

Patented Dec. 3, 1907.

Application filed September 10, 1906. Serial No. 333,951.

To all whom it may concern:

Be it known that I, ARIE DE VOS, a citizen of the United States, residing at Minneapolis, in the county of Hennepin and State of Minnesota, have invented a certain new and useful Electrically-Wound Clock, of which the following is a specification.

The object of my invention is to provide means of simple, durable and inexpensive construction by which a current from an electric battery may be intermittently employed to raise weights for continuously actuating a clock work mechanism and to provide means whereby one of two weights will always remain in an elevated position to avoid the possibility of the clock work mechanism stopping when one of the weights is being elevated, and further to provide an electric contact device by which the contact 20 is automatically broken by the weights in the event that the armature is not moving toward the magnet, when one of the weights is at its lower limit of movement.

My invention consists in the construction, arrangement and combination of the various parts of the device, whereby the objects contemplated are attained, as hereinafter more fully set forth, pointed out in my claims and illustrated in the accompanying drawings, in 30 which—

Figure 1 shows a top or plan view of a part of a clock work mechanism with my improvements applied thereto, and, Fig. 2 shows a side elevation of same with a part of 35 the frame work removed.

Referring to the accompanying drawings, I have used the reference numeral 10 to indicate the frame and 11 to indicate one of a train of pinions for the purpose of illustrating conveniently a clock work mechanism. Mounted in the frame 10 is a rotatable shaft 12 upon which are fixed two ratchet wheels 13 and 14 arranged with their teeth in staggered position relative to each 45 other as illustrated in Fig. 2. Fixed to the same shaft is a pinion 15 in mesh with the pinion 11. Rotatably mounted upon said shaft 12 are two levers 16 and 17, each provided with a spring actuated pawl 18 and 19 50 respectively in engagement with the adjacent ratchet wheels 13 and 14, said levers are provided with weights 20 and 21 respectively. Stops 22 and 23 are provided for limiting the upward movement of the weights. Pivoted

to the levers 16 and 17 are the links 24 and 25 provided with slots 26 and 27. Mounted in the frame 10 is an armature 28 pivotally supported on the bearing points 29 and 30 and having the arms 31 and 32 provided respectively with screws 33 and 34, which screws pass through the slots in the hangers 24 and 25. On the armature 28 on the side of the pivotal point opposite from the arms 31 and 32 is an arm 35 to which a pawl 36 is pivoted, which pawl is provided with a tooth 37 and a projection 38 which serves as a contact point.

The numeral 39 indicates a ratchet wheel rotatably supported on the bearing 40 and provided with a spring actuated detent 41 arranged to prevent its rotation in one direction. A spring 42 normally holds the tooth 37 of the pawl 36 in engagement with said ratchet wheel 39.

The numeral 42^a indicates a contact plate 75 mounted in the insulating block 43, which block has its face above the contact plate 42^a flush with said contact plate.

The electro magnet is indicated by the numeral 44 and the electric battery by the 80 numeral 45. The battery is connected with the electro-magnet by the conductor 46 and this conductor in turn connects with the contact plate 42^a. Another conductor 47 is connected to the pawl 36 and also to the battery forming a complete circuit when the pawl 46 is in engagement with contact plate 42^a.

In practical operation and assuming the parts to be in the position shown in Fig. 90 2, the electric current is broken, because the pawl 36 engages the insulating block 43, the weights 20 and 21 will both descend by gravity until the lower one 21 is in such position that the link 25 thereon will engage 95 the armature and elevate it. If the battery is comparatively strong, the weight will be elevated higher than though the battery was comparatively weak. Therefore, in some instances, the pawls 18 and 19 will 100 move over two teeth of their ratchet wheels 13 and 14 and at other times they will move only one tooth space. However, under no circumstances can they both reach their downward limit at the same time, on account of the staggered arrangement of the 105 teeth on the ratchet wheels, therefore, the clock-work mechanism will never be re-

tarded on account of the upward movement of both weights. During this movement the tooth 37 will engage the adjacent tooth of the ratchet wheel 39 and the lower 5 end of said pawl will be forced outwardly away from contact plate 42^a and downwardly until the next notch between the teeth of the ratchet wheel 39 is reached by the tooth 37, whereupon the spring 42 will 10 quickly throw the pawl 36 into contact with the plate 42^a and firmly maintain said contact. This will cause the electro magnet to be energized and the armature will be quickly drawn downwardly to the magnet 15 and the pawl 36 raised to a point where it passes beyond and out of contact with the plate 42^a. During this movement of the armature toward the magnet, the weight 21 has been elevated to a point above the 20 weight 20, the slots in the links 24 and 25 permitting said movement. The next movement of the armature will be that caused by the weight 20 elevating the armature in the same manner as it was previously elevated 25 by the weight 21. By arranging the two weights relative to one armature in such manner that it is impossible for both of them to be at their lower or upper limit of their movement, at the same time, it will be 30 seen that the clock work mechanism will not stop at the time the weight is at its lower limit of movement and before it is elevated by the armature. Furthermore by the construction and arrangement of the 35 contact breaking and establishing device, the clock work mechanism cannot stop in such position that the contact is established, because the weight of the armature itself and the pressure of the spring 42 both tend to throw the pawl 36 to the position 40 shown in Fig. 2, where the contact is broken. By means of the construction shown, the contact is established only for the smallest possible space of time, that is required to 45 move the armature to its magnet and is broken as soon as this is accomplished. This result is a great saving in the amount of electric current used and consequently the ordinary batteries used for this purpose will 50 last and retain their efficiency for a comparatively long time and the clock work mechanism will run regularly and evenly, because there is a constant pressure upon it by one or the other of the weights all of the 55 time without regard to the time when one of the weights is being moved upwardly.

Having thus described my invention, what I claim and desire to secure by Letters Patent of the United States, therefor is—

60 1. An electrically wound clock, the combination of an electro-magnet, an armature movable to and from the magnet, a weight

elevated by a movement of the armature toward the magnet, said weight during its descent moving the armature away from the 65 magnet, a contact plate and a contact arm both included in a circuit with the electro-magnet and means for moving the contact point across the face of the contact plate out of contact therewith during the movement of 70 the armature away from the magnet and then into contact with the plate before the end of said movement of the armature is reached; said contact arm being also moved out of contact with the said plate when the 75 armature reaches its limit of movement toward the magnet.

2. In an electrically wound clock, the combination of an electro-magnet, a pivoted armature, an arm pivoted to the armature and 80 formed with a tooth and with a contact point, a contact plate, an insulator above the contact plate, a pivoted ratchet wheel, a spring actuated pawl in engagement therewith and a spring for holding the pivoted 85 arm with its tooth in engagement with the ratchet wheel, an electric circuit including the electro-magnet, the contact plate and the contact arm:

3. In an electrically wound clock, the combination of an electro-magnet, an armature movable to and from the magnet, an arm carried by the armature and formed with a tooth and with a contact point, a contact plate in the path of the said contact point, 95 said contact point at one limit of its movement being out of engagement with the contact plate, a notched wheel to be engaged by the tooth of said arm, said wheel arranged to cause the arm to move to position out of contact with the contact plate during part of its movement and then into contact with the plate during another part of its movement. 100

4. In an electrically wound clock, the combination of a rotatable shaft, two ratchet 105 wheels fixed to the shaft with their teeth in staggered positions two weighted levers rotatably mounted upon the shaft, pawls carried by the levers and in engagement with the ratchet wheels, an electro-magnet, an armature movable to and from the magnet and a link pivoted to each lever and having a limited sliding connection with the armature to thereby permit the weights to move upwardly by their momentum beyond the point 115 where they would be positively moved by the armature and the connecting means and to permit independent upward movement of each lever.
